UNITED STATES PATENT OFFICE.

WILLIAM T. SHANNON, OF CINCINNATI, OHIO.

SHEET-METAL CULVERT.

1,071,185.

Specification of Letters Patent.

Patented Aug. 26, 1913.

Application filed March 6, 1913. Serial No. 752,336.

To all whom it may concern:

Be it known that I, WILLIAM T. SHANNON, a citizen of the United States of America, and resident of Cincinnati, county 5 of Hamilton, and State of Ohio, have invented certain new and useful Improvements in Sheet-Metal Culverts, of which the following is a specification.

This invention relates to conduits and has 10 for an object to produce a metal conduit composed of sheet metal sections and having improved means for interlocking separate sections.

A further object is to produce a metal conduit section having a substantially flat bottom plate, which is provided with improved means for removably securing it to adjacent bottom plates.

A further object is to produce a metal 20 conduit provided with means for securing the separate sections together and for preventing a flow of water between the conduit and its supporting foundation.

These and other objects I attain by means 25 of a metallic structure embodying the features herein described and illustrated in the drawings accompanying and forming a part of this application.

In the drawings Figure 1 is a fragmental 30 perspective view of a conduit embodying my invention. Fig. 2 is a fragmental perspective view of a base plate which forms a detail of my invention, and Fig. 3 is a longitudinal section of a conduit embodying 35 my invention.

My present invention is embodied in a metallic conduit which, as illustrated, is formed in separate sections, each section consisting of a substantially flat plate 5, and 40 an arched cover plate 6. The parts 5 and 6 are so arranged that each section may be quickly and easily assembled and the separate sections may be readily secured together without the necessity of employing 45 rivets or other fastening means which are difficult to adjust.

As illustrated, each plate 5 is formed from a sheet metal blank and is preferably provided with longitudinally extending 50 grooves 7, which are located along its lateral edges and are adapted to receive the lateral or straight edges of the arched cover plates 6. Each plate 5 is also provided with downwardly extending flanges 8, which are 55 located along the lateral edges of the plate,

immediately adjacent to the grooves 7. Each plate 5 is also provided with a downwardly projecting flange or tongue 9, which, as illustrated, is integrally formed with, or is struck from, the metal of the plate and extends transversely along one end of the plate, between the grooves 7. The other end of each plate is provided with a transversely extending slot 11, which is preferably formed in the metal of the plates so as to form a correspondingly located ridge 11' on the bottom of the plate. This ridge 11' extends across the plate and between the grooves 7, and projects downwardly below the bottom face of the plate 5, and, besides stiffening the end of the plate, it forms a flow obstructing ridge which projects below the plate and extends between it and its support or foundation.

Each slot 11 is adapted to receive the 75 tongue 9 of an adjacent plate, during the operation of assembling the sections to form a conduit, and the tongues and grooves of adjacent plates coöperate to lock the plates together and also to form stiffening ribs for 80 the finished conduit. These stiffening ribs not only strengthen the bottom plates against cross-bending, but also prevent the culvert from buckling, due to an unequal distribution of the load on the arched 85 plate 6.

Each flange 9 is preferably formed by slitting one edge of the sheet metal, forming the plate, at points adjacent to the grooves 7, and then turning the severed portion of the blank downwardly, so that it extends transversely across the plate between the grooves 7. The ridge 11' is formed in substantially the same manner, except that the outer edge of the partially severed piece of metal is turned upwardly so as to form the slot 11. The depth and the width of the slots 11 are so proportioned that tongues 9 of adjacent plates are readily received by them.

During the assembling of the separate sections to form a conduit, the plates 5 are located end to end, so that the tongue 9 of one plate projects into, and is held in place by, the slot 11 of an adjacent plate. When 105 the plates are in this position, the metal forming the grooves 7 of one plate overlaps the metal forming the grooves 7 of an adjacent plate and the grooves coöperate to interlock the plates of the series, included 110

in the conduit, and to prevent them being displaced laterally, relatively to each other. The grooves 7 also coöperate to form a continuous groove, along each edge of the base 5 portion of the conduit, and in which the straight edges of the arched members 6 are located. I find it preferable to so locate the plates 5 during the formation of a conduit, or culvert, that the slots 11 are turned to 10 ward the uphill end of the conduit. With such an arrangement, the downhill end of each plate overlaps the uphill end of the next adjacent plate, and consequently, produces an effective draining surface and a 15 substantially water-tight construction.

With the plates 5 constructed as illustrated, each plate is supported by the ribs, formed on the bottom of the plate and resulting from the formation of the grooves 7. 20 These ribs extend downwardly below the bottom of the plate, the same amount as the transversely extending ridge 11'. With this construction the flat or body portions of the plates are located above their supporting foundation, when a rigid foundation is employed, and the space below the plates and between them and their foundation is intersected at intervals by the transversely extending ridges 11'. It is well known that 25 water will flow along the line of least resistance, and that, where the bottom plates of a culvert, of the type illustrated, are mounted immediately upon the earth without the intervention of a solid foundation, 30 a stream of water is likely to be formed under the culvert, which, if it is unobstructed, will gradually undermine the culvert and eventually wreck it. The transversely extending ridges 11' which project downwardly below the plates 5, obstruct and 35 tend to wholly prevent such a flow of water under the culvert or conduit; and they consequently prevent the foundation of the culvert from being washed or worn away. By 40 turning the plates 5 so that the downhill end of each plate overlaps the uphill end of each adjacent plate, means is provided for adequately draining water from below the plates into the culvert, since the water 45 below the plate will pass through the crevices or cracks between the adjacent plates and enter the culvert. The fact that the 50 grooves 7 are substantially as deep as the ridges 11' also aids in draining water from 55 below the plates 5 into the conduit, since the ridges 11' obstruct the flow of water below the culvert, and the path of least resistance for the confined water is through the crevices between the metal of the plates forming the grooves.

In the drawings the arched plates 6 are shown corrugated for the purpose of strengthening them, and in Fig. 3, these plates are shown overlapped so that the end 60 corrugation of one plate interlocks with the

end corrugation of an adjacent plate. This construction produces an arched culvert in which the separate parts are as effectively held together, for all practical purposes, as if bolts, rivets, or similar devices were employed. In addition to this, the bottom plates are strengthened longitudinally by the formation of the grooves 7, and they are strengthened laterally by the formation of the tongues 9 and ridges 11', so that the culvert sections are stronger than other metal sections now in use and employing the same weight of metal. The coöperation of the tongues 9 and ridges 11' also increases the lateral strength of the bottom plates of the culvert, since, in practice, the culvert will be reinforced at points, substantially two and one-half or three feet apart, by a rib formed of three thicknesses of metal and reinforced by the inherent rigidity of the metal of the plates on which its coöperating parts are formed. Such a construction will not only insure against cross-bending of the plates 5, but it will prevent the plates from buckling and will also increase the rigidity 90 of the finished conduit.

By forming the grooves 7 and the slots 11 so that they project below the bottom face of the plate, the culvert will be securely anchored in place when it is mounted directly upon the earth, since the weight of the culvert and the weight of the earth above it will force the downwardly projecting ridges or ribs, formed on the bottom of the plates 5, into the supporting earth, and this will also render the transversely extending ridges 11' more effective as flow-obstructing agents.

The advantage of the construction, herein illustrated, is that the culvert or conduit may be formed of galvanized or protected sheet metal, in which each plate or section is completely covered by the protective sheath of the galvanizing metal. Such a construction is impossible where the separate sections are riveted or are secured together by means of bolts or similar devices. Another advantage is, that the plates are so interlocked by the coöperation of the groove 7 and the tongues 9 and slots 11 of the different plates, that they are prevented from moving in both directions relatively to each other.

While I have illustrated and described a preferred embodiment of my invention, I desire to have it understood that various 120 changes, modifications and substitutions may be made in the apparatus illustrated, without departing from the spirit and scope of my invention as set forth in the appended claims.

What I claim is:

1. A substantially flat bottom plate for conduit sections, having a tongue receiving slot formed across one end thereof.
2. A substantially flat bottom plate for 130

conduit sections, having a tongue at one end and a tongue-engaging slot at the other end thereof.

3. A substantially flat bottom plate for 5 conduit sections, having a flow obstructing stiffening rib formed thereon and provided with a tongue-engaging slot.

4. A substantially flat bottom plate for 10 conduit sections, having a downwardly projecting stiffening flange extending across the plate at one end thereof, and a flow obstructing stiffening rib extending transversely across the plate and having a flange-engaging slot formed therein.

15 5. A substantially flat bottom plate for conduit sections, having longitudinally extending supporting ridges located along its lateral edges, a transversely extending flange located along one end thereof, and a trans- 20 versely extending flange-engaging slot formed along the other end thereof.

6. In a conduit section, a top member and a bottom member, comprising a substantially flat plate having longitudinally extending top member-engaging grooves, and a transversely extending flange-engaging slot formed therein.

7. A substantially flat sheet metal bottom plate for conduit sections, having longitudinally extending supporting ridges and a transversely extending flow obstructing ridge formed on the bottom face thereof, and a downwardly projecting locking flange formed at one end thereof.

35 8. A conduit composed of sheet metal cover plates and substantially flat interlocking sheet metal bottom plates provided along their lateral edges with means for engaging the cover plates.

40 9. A conduit composed of interlocking bottom plates having longitudinally extending cover plate-receiving grooves formed therein, and arched cover plates mounted on the bottom plates with their lateral edges in 45 the grooves.

10. A conduit composed of interlocking bottom plates having flow-obstructing ribs formed thereon and top-receiving grooves formed therein, and overlapping arched 50 cover plates mounted on the bottom plates

with their lateral edges mounted in said grooves.

11. A conduit composed of a series of interlocking sections, each section comprising a bottom plate having cover-receiving grooves formed therein, a flange on one end thereof and a flange-receiving slot formed in the other end thereof, and a cover plate mounted on the bottom plate and having its edges mounted in the grooves formed in the 60 cover plate.

12. A conduit composed of a series of interlocking sections, each section comprising a bottom plate, having an interlocking flange formed thereon, and a flow-obstructing and flange-engaging ridge formed thereon and adapted to engage an interlocking flange of an adjacent plate, and a cover plate mounted on the bottom plate.

13. A conduit composed of sheet metal 70 sections, each section consisting of a cover and a substantially flat sheet metal bottom plate provided along one end with an integrally formed, downwardly projecting flange, and along the other end with a transversely extending stiffening rib having a flange-engaging slot, and along its lateral edges with means for engaging the cover.

14. A substantially flat bottom plate for 80 conduit sections, having longitudinally extending lateral grooves formed therein, and a transversely extending slot formed along one end thereof, the metal of the grooves projecting beyond the slot.

15. A substantially flat bottom plate for 85 conduit sections, having a downwardly projecting flange at one end and a downwardly projecting flange-engaging ridge at the other end, and longitudinally extending lateral grooves; formed therein, the metal forming 90 the grooves projecting beyond the flange and the ridge at their respective ends of the plate.

In testimony whereof, I have hereunto subscribed my name this 3rd day of March, 95 1913.

WILLIAM T. SHANNON.
